UNITED STATES PATENT OFFICE.

LOUIS EDWARD LEVY AND MAX LEVY, OF PHILADELPHIA, PENNSYLVANIA, ASSIGNEES
TO GRAPHIC ARTS CO., OF PHILADELPHIA, PENNSYLVANIA, A CORPORATION OF NEW
JERSEY

ETCHING-MACHINE.

No. 920,766.

Specification of Letters Patent.

Patented May 4, 1909.

Application filed August 27, 1906. Serial No. 332,240.

To all whom it may concern:

Be it known that we, LOUIS EDWARD LEVY and MAX LEVY, citizens of the United States, and residents of Philadelphia, in the county of Philadelphia and State of Pennsylvania, have jointly invented new and useful Improvements in Etching-Machines, of which the following is a specification.

Our invention relates to improvements in etching machines, the purpose thereof being to provide a simple and effective apparatus for projecting an erodent or etching fluid against the surface of a plate, to erode or etch the unprotected parts of its surface, the apparatus forming the subject matter of this application being used to more effectively carry into effect the "Levy acid blast method of etching," in which method the etching fluid is projected upward against the under surface of a horizontally supported plate.

Our present invention includes means for exhausting from an etching-chamber, the fumes or vapors that are generated during the process of etching, such fumes or vapors being condensed, a part being returned to the etching-chamber for further use, means also being provided for preventing the escape of fumes or vapors so that the atmosphere about the machine will not be vitiated.

In an apparatus made in accord with our invention, there is present an acid-chamber and connected therewith is an air-chamber which communicates with the acid-chamber solely by passages through aspirating atomizers or nozzles; the acid-chamber which is more or less open to the atmosphere is connected to exhaust mechanism, and the air-chamber is connected with a blower or air compressor, the arrangement being such that during the process of etching the vapors, fumes or gases and air are drawn from the etching-chamber, so that in operation less than atmospheric pressure will be maintained in said etching-chamber and at the same time air under pressure is supplied to the atomizers, to project acid on the plate to etch the same, and with an apparatus made in accord with our invention, pressure greater than that of the atmosphere is maintained in the air-chamber and a partial vacuum is kept up in the etching-chamber.

Another feature of our invention appertains to the plate-carrier or carriage, such plate-carrier being adapted to be detached from mechanism that imparts a reciprocating motion thereto, so that the carriage when detached from its reciprocating mechanism may be moved toward front of the apparatus and raised to expose the surface of the plate.

The circulating system used in carrying into use our invention includes an etching-chamber, a partial cover therefor, an air-chamber that communicates with the etching-chamber by air vents or passages through atomizing nozzles or aspirators, means for effecting an inflow of air to the etching-chamber, a condenser for the fumes, vapors or gaseous products that are evolved during the process of etching, a pipe connected to the blower or pump and a by-pass or valve for the escape of a part of the fumes and vapors so arranged that in use pressure will be maintained in the air-chamber and a partial vacuum in the etching-chamber.

Our invention also includes several novel features of construction and arrangement of parts, as will be hereinafter set forth.

In the accompanying drawings illustrating our invention, Figure 1 is a side elevation, and in this view the carriage and its plate carrier is shown by dotted or broken lines in a raised position. Fig. 2 is a top view of the machine. Fig. 3 is a transverse section, on the line 3—3 of Fig. 2, showing the bridge, the plate carrier and frames that rest upon the tanks. Fig. 4 is a longitudinal section of the plate-carrier. Fig. 5 is a top view of the tanks. Fig. 6 is a longitudinal section of the tanks, on the line 6—6 of Fig. 5. Fig. 7 is a detail section, on the line 7—7 of Fig. 5. Fig. 8 is an inverted plan view of one of the baffle-plates of the condenser. Fig. 9 is a sectional view of one of the sprayers. Fig. 10 is a sectional view of one of the acid atomizing nozzles, and Fig. 11 is a plan view of the fixed part of the nozzle shown by Fig. 10.

In an apparatus as illustrated a suitable stand or frame carries a drip-pan 12 and above the pan are tanks or receptacles 13 and 14 preferably made of porcelain, terra-cotta or other suitable acid-proof material, such tanks having interlocking ends and a covering piece above the connected ends. The floor of the washing-chamber or tank 13

has therethrough apertures for the passage of parts of couplings which are engaged by nuts to which are secured sprayers 10, see Fig. 9, made preferably of porcelain, and to 5 the couplings below the bottom of the tank are secured pipes 9 which are connected by branch-pipes to a water-supply pipe 6, such pipe having a valve located to be within easy reach of the operator. The outlet opening 10 of the tank 13 is connected by a trap with a waste pipe 25.

The etching tank 14, is divided horizontally by a perforated partition 15, and below the partition there is a chamber 16 for air and 15 gases under compression, which are admitted thereto through an opening 17; the chamber 16 is also provided with an eduction opening which is connected to the waste-pipe 25 by a pipe or coupling 18 having a valve 19. The 20 perforated partition 15 carries a plurality of atomizing nozzles or aspirators that are made in two parts, the fixed or lower part 20, having a conical portion below which is a threaded extension that engages the partition 25 about the perforations, and above the conical part projects a tip; the shoulder between the tip and the conical portion and the tip have ribs 21, and the passage through the fixed part of the nozzle is contracted at the 30 discharge. The movable part or cap 22 of the nozzle rests upon the ribs 21 the lower edge being maintained above the upper surface of the partition 15, and the opening through the upper end of the cap is slightly 35 larger in diameter than the opening through the tip, the construction providing a self centering nozzle and one that will adapt itself to the proper projection of the etching fluid under varying air pressures and depths of 40 liquid in the etching chamber. Several of the nozzles have in communication with the openings therethrough depending tubes 11 that are either perforated at their lower ends or open, the purpose of the tubes being to 45 draw from the chamber 16 any liquid that may accumulate therein. The atomizing nozzles or aspirators are arranged in longitudinal and transverse rows, they being placed closer together transversely than longitudinally.

The acid chamber 14 is connected by a passage to a funnel 23 that is formed integral with the chamber, and below the passage is a conical seat for a plug 24, and below the 55 seat for the plug the funnel is connected by a suitable coupling to the drain pipe 25. The shape of the funnel enables the operator to readily ascertain the level of the liquid in the acid chamber. The acid chamber or etching 60 tank 14, to one side of the funnel 23 has a hollow offset that communicates with the etching chamber 14, and upon the hollow offset is placed the shell of a condenser, such shell 65 being constructed to receive a series of baffle-plates 27; the plates 27 are cut-away

on one edge and have legs or projections so that when placed in the shell one above the other a circuitous passage will be provided for the vapor or gases, which are drawn therethrough by a pump or other exhaust 70 mechanism 30, and the vapor or gases are condensed in the shell the liquid being returned to the etching chamber. The upper end of the shell or condensing chamber 26 is connected by a suitable casing 28 with the 75 induction pipe 29 of a pump or blower 30; the eduction pipe 31 extends from a trap 8 to the eduction opening of the pump or blower 30, the pipe 31 being coupled to the opening 17 through the end wall of the air chamber 16. 80 The eduction pipe 31 adjacent to the opening 17 has a by-pass or valved coupling 60, of ordinary construction the stem of the valve having a bar or lever 61 that is attached to a rod 62 which extends to the front of the machine, and when the rod is properly moved the valve is positioned so that a portion of the exhaust may pass into the waste pipe 25, the balance being forced into the air chamber to maintain therein a pressure that is 90 greater than that of the atmosphere. The by-pass valve and its connections place under control of the operator the pressure within the chamber 16, so that the amount of liquid projected by the atomizers may be regulated without changing the speed of the pump or blower; the adjusting of the valve and the revolutions of the pump or blower will also determine the reduction of pressure 95 in the etching chamber.

The frame that is supported by the upper edges of the tanks 13 and 14, has on its inner portion an inward projecting flange 33 and a depending part that overlies the inner edges of the tanks; the angle bar 34 that forms the outer portion of the frame has attached thereto brackets to which are secured arches 35 a bridge-plate 36. The upper portions of the arches 35 have bearings for a driven shaft 37 which has thereon a gear 38 that meshes with a larger gear 39 carried by a crank-shaft 40, such shaft being journaled in bearings attached to or formed integral with the bridge-plate 36. The crank on the shaft 40 has secured thereto a connecting rod 41, the front end of which engages a slide 42, that reciprocates in a guide 43 carried by the bridge-plate 36. The front end of the slide 42 is shaped to provide a catch 44, with which a transverse bar 46 of the bail engages 105 to reciprocate the carriage or plate carrier. The side bars 45 of the bail being attached to the axles of the rear wheels of the carriage or plate-carrier. The transverse portion of the bridge has attached to its underside a partial covering plate 47 for the etching-chamber, the rear section 74 of such plate being secured to a leaf 75 that is hinged to the bridge-plate 36, and when the carriage or plate carrier is moved forward that part 74 110 115 120 125 130

of the covering plate that is over the rear end of the etching chamber may be raised so that access may be had to the interior of the etching-chamber.

5 Each of the side pieces 48 of the carriage or plate carrier has stub axles for wheels that engage the upper edges of the frame and the tracks 49 and when the front cross-bar 46 of the bail is disengaged from the hook 44 the carriage 10 may be moved forward. When the carriage or plate-carrier is moved forward the front wheels will ride upon the inclined portion of the tracks 49, and will incline the carriage and plate to drain such etching fluid as may 15 adhere to the plate and the plate holder into the etching chamber before the plate carrier assumes a horizontal position over the washing tank.

The side pieces 48 of the carriage or plate 20 carrier are connected by a transverse plate 50, which may be of greater width than the covering plate 47 for the etching chamber, and the side pieces above the point of attachment of the stub axles have secured 25 thereto parallel bars 51 on which are mounted adjustable clamps that carry a flat bar 52, such bar lying transversely below the plate 50, one edge of the plate 50 and the edge of the bar 52 being shaped to engage the edges 30 of the plate to be etched, such plate being held on the carriage or plate-carrier with its back against the underside of the plate 50.

The stub axles 53 on the rear of the carriage or plate carrier are engaged by the rear 35 ends of the side bars 45 of the bail and the front bar 46 of such bail when the carriage is in position over the etching chamber, is engaged by the hook 44 so that when the shaft 37 is turned a reciprocatory movement will 40 be imparted to the carriage.

The frame that is supported upon the upper edges of the tanks has adjacent to the rear end of the water chamber stops or upward projections 55, and the carriage has 45 tensions 54 so that when the carriage is moved forward and raised to a rearward inclined position, to attach a plate to the plate holder or to inspect the plate after being etched, the end extensions of the carriage 50 will engage the stops.

The covering plate 47 and its hinged section 74 which are carried by the bridge are of less width than the tanks, and the sides of the carriage move in the space between the 55 frame and the covering plates, so that there will be about the sides and ends of the etching chamber a space through which air will be admitted to the etching chamber, when the exhaust mechanism connected therewith 60 is in operation.

In operation the carriage or plate-carrier to which the plate to be etched has been secured is moved over the etching chamber, etching fluid having been placed therein in 65 sufficient quantity to cover the lower por-

tions of the aspirators, the shaft that is supported by the bridge being turned reciprocates the carriage with its attached plate, moving the plate back and forth a distance about the same as the space between the 70 transverse rows of aspirators. The pump or blower being driven forces air into the chamber below the etching chamber and through the aspirators, projecting the etching-fluid against the reciprocating plate. The chemical action of the etching-fluid upon the unprotected parts of the plate produces fumes, heat and gases which increases or adds to the contents of the etching-chamber, and to prevent the fumes and gases escaping and 75 vitiating the atmosphere about the machine, and to recover a part of the etching fluid, the gases or other products generated by the contact of the etching fluid with the metallic plate that is being etched are drawn from 80 the etching-chamber, the suction of the pump or blower, reduces the pressure in the etching-chamber below that of the atmosphere; such reduction of pressure or partial vacuum in the etching-chamber causes an 85 inflow of air about the edges of the covering plate into said etching-chamber. The vapors that are drawn from the etching-chamber by the pump or blower are first caused to pass about a series of baffle-plates, the etching-fluid constituting a part of such vapors being condensed thereon will flow back to 90 the etching-chamber. The exhaust opening of the etching-chamber, the condenser and the duct therefrom are connected to the 100 pump and the pipe from the eduction opening of the pump or blower leads to the trap 8, the pipe from such trap adjacent to the opening to the air chamber 16 having a bypass valve under control of the operator so 105 that a part of the discharge will enter the drain pipe, the balance of air under compression intermixed with the products that are carried over from the etching-chamber, enter under pressure the air-chamber and 110 pass therefrom through the aspirators, to project the etching-fluid against the plate to be etched.

If desired the full quantity of air under compression may be admitted to the air-chamber and such chamber may have a valved outlet opening so that the air in excess of what is required with the condensations may escape, and in operation there is always a partial vacuum in the etching-chamber, and in the chamber below the aspirators the pressure will be maintained in 115 excess of atmospheric pressure.

The plate after being etched may be moved toward the washing-tank, such movement inclining the plate so that particles of etching-fluid will drain therefrom into the etching-chamber, the carriage is lifted to incline the same and expose to view the plate, and when lowered to a horizontal position it 120

is washed by water projected through the nozzles attached to the bottom of the washing-tank.

We claim.

- 5 1. In an etching apparatus, the combination of an etching chamber, a partial closure therefor, a holder for the plate to be etched, an air-chamber, atomizers having openings therethrough which communicate with the 10 air-chamber and with the etching chamber, and means for maintaining in the etching-chamber a partial vacuum and in the air-chamber pressure greater than that of the atmosphere.
- 15 2. In an apparatus for etching metal plates, the combination of an etching-chamber, a partial cover therefor, a holder for the plate to be etched which is adapted to maintain the plate below the partial cover for the 20 etching-chamber, a chamber for air under pressure below the etching-chamber, atomizers in the etching-chamber which have air passages that communicate with the air-chamber, and means for partially exhausting 25 the etching-chamber and simultaneously producing in the air-chamber pressure which is greater than the pressure of the atmosphere.
3. In an etching apparatus, an etching-chamber that is partially open to the atmosphere, means therein for projecting etching-fluid upward against a plate maintained in such etching-chamber, means for exhausting from the etching-chamber during the process of etching the fumes and gases generated in 35 the etching-chamber by contact of the etching fluid with the plate and at the same time causing an inflow of air to such chamber.
4. In an etching apparatus, an etching chamber, atomizers for projecting by means 40 of air under compression etching fluid against a plate maintained in the chamber above the atomizers, means for exhausting from the etching-chamber, the products generated by contact of the etching-fluid with the plate to 45 be etched, and means for condensing such products and returning them to the etching chamber.
5. In an apparatus for etching metal plates, a partially closed etching chamber, a 50 chamber beneath the same which communicates with the etching chamber and unitary means for maintaining in the etching chamber a partial vacuum and in the other chamber pressure in excess of that of the atmosphere.
6. In an apparatus for etching metal plates, an etching chamber which is partially open to the atmosphere, means for maintaining a plate in such chamber so that it will be 60 subjected to the action of an etching fluid, and means for maintaining a partial vacuum in the etching chamber to cause an inflow of air thereto.
7. In an etching apparatus, a partially 65 closed etching chamber, means connected

with the etching chamber to effect an inflow of air thereto, inlet and exhaust openings both positioned above the floor of the etching chamber, and air-supply openings through the floor of the etching chamber.

70

8. An etching apparatus having an etching chamber which is partially open to the atmosphere, atomizers through which air is forced into the etching chamber, and means for maintaining a partial vacuum in the 75 etching chamber.

9. In an etching apparatus, an etching-chamber which is partially open to the atmosphere, an air-chamber connected therewith, a plurality of atomizers attached to the wall between the etching chamber and the air chamber, an opening through one of the other walls of the etching chamber that is connected with means for maintaining in the etching chamber a partial vacuum, a funnel that communicates with the etching chamber to supply the same with etching fluid, a stopper seated below the opening between the funnel and the etching chamber, means for maintaining in the air chamber 90 pressure sufficient to force air through the atomizers and project etching fluid against a plate maintained above the atomizers.

90

10. In an etching apparatus, an etching chamber which is partially open to the atmosphere, an exhaust opening through one of the walls of the chamber, a condenser having as a part thereof a series of baffle plates, said condenser being maintained at a higher elevation than the exhaust opening, 95 exhaust mechanism connected with the condenser for maintaining a partial vacuum in the etching chamber, a series of atomizers an air chamber that communicates with the etching chamber through such series of atomizers, a pipe connecting the exhaust mechanism with the air chamber to maintain therein sufficient pressure to project etching fluid against a plate maintained above the atomizers, and an opening through which the compressed air and gases not required to project the etching fluid may escape, substantially as set forth.

100

11. In an etching apparatus, an etching chamber having therein atomizers, a chamber that communicates with the etching chamber through the atomizers, a pump or blower connected with the etching chamber and with the air chamber, a waste pipe means for shunting a portion of the air and 110 gases drawn from the etching chamber into the waste pipe, the compressed air and gases that pass through the atomizers projecting etching fluid against a plate maintained above the atomizers.

115

12. In an etching apparatus, a tank divided by a partition a plurality of atomizers carried by the partition, openings through the atomizers which connect the chambers above and below the partition, one or more 120

125

13. In an etching apparatus, a partially closed etching chamber, means connected

tubes that extend from one or more of the atomizers to the bottom of the lower chamber for drawing from the lower chamber liquid that may accumulate therein; and 5 means for exhausting from the upper chamber gases and vapors generated therein and forcing a portion of such gases and vapors into the lower chamber and from thence into the upper chamber through the atomizers. 10

13. In an etching apparatus, a partially closed etching chamber, a plate holder adapted to support a plate to be etched over the etching chamber, a plurality of atomizers, an air chamber below the etching chamber and in communication therewith through the atomizers, a pump or blower connected with both of the chambers and operating to withdraw from the etching chamber vapors 15 and gases evolved by contact of the etching fluid with the plate to be etched and to effect an inflow of air to the etching chamber, the pump or blower also forcing a portion of the air, vapors and gases that are drawn 20 from the etching chamber into the air chamber and through the atomizers to project etching fluid against the plate, and a valve under control of the operator to direct otherwise than into the air chamber the air; 25 vapors and gases that are not needed to project the etching fluid.

14. In an etching apparatus, an etching and a washing chamber which are both open to the atmosphere, a plate-carrier and a partial cover for the etching chamber, ways 30 upon which the plate-carrier may be moved; the ways having inclined portions upon which the plate-carrier will ride when moved toward the washing chamber, for the purpose 35 set forth.

15. In an etching apparatus, an etching chamber, a plate washing chamber adjacent thereto, a frame mounted on the etching chamber, carriage engaging and reciprocating means carried by the frame, a carriage 40 mounted to be movable over the etching-chamber, means for attaching a plate to the carriage, and means for maintaining the

carriage in an inclined position to expose to view the plate. 50

16. In an etching apparatus, an etching chamber and a washing chamber, a plate-supporting-carriage which is movable over the chambers, a bail attached to the carriage, means with which the bail may be placed in engagement to reciprocate the plate-supporting carriage when over the etching chamber. 55

17. The combination in an etching apparatus, an etching chamber, a washing chamber, a frame mounted upon said chambers, a bridge attached to the frame and provided with a partial cover for the etching chamber, a carriage mounted to be movable upon the frame, a plate-holder attached to the carriage to maintain a plate under the partial cover for the etching chamber, a bail attached to the carriage and adapted to be placed in engagement with reciprocatory means carried by the bridge, 60 projections on the carriage and stops on the frame which may be brought into engagement when the carriage is raised, substantially as shown. 65

18. An etching apparatus, comprising a partially open etching chamber, a conduit from the etching chamber, and means 70 adapted to cause a current of air to pass into the etching chamber and from said chamber into the conduit. 75

19. An etching apparatus having an etching chamber, a conduit in communication with the etching chamber, and means for drawing air into the etching chamber and out of the same through the conduit; for the purpose of withdrawing from the etching chamber the fumes generated therein, and to prevent the temperature being unduly raised in the chamber. 80 85
